(57) **CLAIM**

The ornamental design for a display panel or portion thereof with touch controls for a cooking appliance as shown and described.

DESCRIPTION

FIG. 1 is a front view of a first embodiment of a display panel or portion thereof with touch controls for a cooking appliance showing the new design;

FIG. 2 is a front view of a second embodiment of a display panel or portion thereof with touch controls for a cooking appliance showing the new design; and,

FIG. 3 is a front view of a third embodiment of a display panel or portion thereof with touch controls for a cooking appliance showing the new design.

The display panel or portion thereof with touch controls for a cooking appliance is substantially flat. The broken lines are for environmental purposes only and do not form any part of the claimed design.

1 Claim, 3 Drawing Sheets
